INVENTOR

Thayer A. Hill.

UNITED STATES PATENT OFFICE.

THOMAS A. HILL, OF NEW YORK, N. Y.

GUARD AND CURB.

1,105,781.

Specification of Letters Patent.

Patented Aug. 4, 1914.

Application filed July 29, 1913. Serial No. 781,768.

To all whom it may concern:

Be it known that I, THOMAS A. HILL, a citizen of the United States, residing at the borough of Brooklyn, county of Kings, city 5 and State of New York, have invented certain new and useful Improvements in Guards and Curbs, of which the following is a specification, reference being had therein to the accompanying drawing.

10 My invention relates to improvements in guards or curbs, and more particularly has reference to a wheel-guard or curb to prevent the hub of the wheel or body of the vehicle to which it is attached from coming 15 in contact with the wall, fence, partition or other structure to be protected.

This guard is adapted to be secured at the base of the wall, fence or other structure and is preferably so made that the same may 20 be renewed in part so as to replace parts worn by contact with vehicles.

Referring to the accompanying drawings, Figure 1 is a plan view, partly broken away and partly in section, illustrating one application of my invention. Fig. 2 is an end view looking upwardly at Fig. 1. Fig. 3 is an enlarged section in plan view similar to that shown in Fig. 1, and Fig. 4 is an enlarged end view similar to that shown in 30 Fig. 2 except that the parts are held by screws instead of rivets, and Fig. 5 is a cross sectional view of a modification.

6 indicates a board-fence or railing supported by the vertical beams 7, to the base 35 of which is secured an angle iron such as 8.

9 is a metal plate secured to the angle iron 8 and the angle 10 as shown, and 11 is a suitable support such as a channel beam upon the top of which is preferably secured 40 the inside angle 12 to which the channel 11 is secured and to the angle 10 by the rivet 13 or other suitable means, the rivet 14 being adapted to pass through both angles 10 and 12 and the plate 9 as shown. By reference 45 to Fig. 4 it will be observed that instead of rivets, screws such as 13' and 14' may be employed so that by constant wearing of the wheels on the face of the angle 10 the same may be readily removed by withdrawing the screws 13'-14' and placing a new

outside angle or wearing portion such as 10 in position.

In the modification shown in Fig. 5, the plate 9' may be mounted on any suitable standard such as 15 by any suitable means 55 and is preferably inclined as shown so as to enable the snow and rain to readily escape without unnecessarily rusting the structure.

Of course it will be understood that an integral Z-shaped beam may be employed 60 instead of using angle irons as stated. It will also be understood that suitable pipes, cables or other devices such as 16 may be stored within the guard or curb as shown; thus enabling the same to serve as a conduit 65 or box for the protection of such pipe, conduit or cable.

Of course it will be understood that various modifications may be made without departing from the spirit of the invention 70 as claimed.

I claim:

1. In a combination with a structure to be protected, a guard comprising a web portion disposed at an angle to said structure, 75 and adapted to be secured adjacent thereto, and a front depending wearing edge for said web whereby the hubs of vehicles are prevented from striking said structure.

2. In combination with a structure to be 80 protected, a guard comprising a web portion disposed at an angle to said structure and adapted to be secured adjacent thereto, and a front depending wearing edge for said web whereby the hubs of vehicles are pre- 85 vented from striking said structure, said wearing edge being adapted to be removed.

3. A wheel-guard comprising a central plate having an angle iron at the back adapted to be secured to a post, and an angle 90 iron at the front projecting downwardly from said plate, and means beneath said plate for securing the same in position.

4. A wheel-guard comprising a central plate having an angle iron at the back 95 adapted to be secured to a post, and an angle iron at the front projecting downwardly from said plate, and means beneath said plate for securing the same in position, said means comprising an angle iron beneath 100

said plate and a channel beam, said angle iron, plate and channel beam secured together.

5. A wheel guard comprising a plate having an angle iron at the back, and an angle iron at the front projecting downwardly from said plate, means for securing said guard in position, and means for detachably

securing said angle iron at the front of said plate.

In testimony whereof I hereunto affix my signature in the presence of two witnesses.

THOMAS A. HILL.

Witnesses:
